UNITED STATES PATENT OFFICE

JOHN WILLIAM RADBURN, OF RUSHDEN, ENGLAND

MEANS FOR GROOVING OR SCORING LEATHER

Application filed April 27, 1929, Serial No. 353,679, and in Great Britain April 16, 1929.

This invention relates to means for grooving or scoring leather, the means being of the kind comprising series of discs provided with peripheral projections and mounted on a 5 rotatable shaft for scoring or grooving pieces of leather, and in particular the bevelled or chamfered margins of soles of footwear, for the purpose of improving the adhesion between the pieces of leather or soles and 10 the inner soles and uppers of footwear when secured together by an adhesive; and its primary object is to facilitate such grooving or scoring, especially in connection with comparatively thin pieces of leather or soles, such 15 as are used for the soles of dancing and similar shoes, such soles being of insufficient thickness to enable them to be effectively held against the grooving or scoring means solely through the body of the leather forming 20 the sole.

According to the invention, a movable member serves to support the margins or portions of the pieces of leather or soles evenly and closely against the grooving or scoring means. The supporting means not only facilitates the grooving or scoring of the said margins or portions but also ensures an improved result and obviates injury to the hands of the operator through not having to press the margins or portions of the pieces of leather or soles against the said means with his hands. To further facilitate the grooving or scoring operation there is provided in connection with the movable supporting member a table on which the operator can place the pieces of leather or soles to be operated upon by the aforesaid means. The grooving or scoring means comprise a series of apertured discs of known form provided with teeth or projections and arranged on a spindle capable of being rotated at a comparatively high speed. Preferably, the discs are so arranged that the teeth of the successive discs are staggered or occur in oblique or spiral lines in order to form grooves or scores in the said margins or portions. To ensure the outer thin edges of the bevelled or chamfered margins of the pieces of leather or soles not being torn or rendered rough the outer disc of the series of discs constitut-

ing the grooving or scoring means comprises a continuous cutting edge. It will be understood that the use of such a continuous cutting edge renders unnecessary any finishing operation to the pieces of leather or soles 55 prior to the attachment thereof by an adhesive, as is found necessary in some cases when only toothed discs are employed.

In order that the said invention may be clearly understood and readily carried into effect, the same will now be more fully described, by way of example with reference to the accompanying drawings, in which:—

Figure 1 illustrates in sectional elevation an arrangement constructed according to the 55 invention;

Figures 2 and 3 are face views of two forms of discs made use of in the grooving or scoring means.

The movable supporting means in the construction illustrated in the drawings consists of a roller or wheel *a* formed with a bevelled periphery and so arranged relatively to a table *b* that a part of the bevelled surface of larger diameter projects through an aperture *b'* provided therefor. The table *b* is inclined at a different angle from that of the bevel of the roller or wheel *a*, the difference being such that the portion of the roller or wheel *a* of smaller diameter is always flush at 70 that part where the roller or wheel *a* extends into the aperture *b'*, while the portion of larger diameter projects through the aperture and above the surface of the table *b*. Above the table *b* and over the roller or wheel *a* is disposed the grooving or scoring means 75 comprising a series of discs *c* mounted on a spindle *d* capable of being rotated at a high speed through the pulley *e*. The disc with the continuous cutting edge is designated *f* 80 and is disposed over the portion of the roller or wheel *a* of larger diameter. The discs are secured to the shaft between nuts *g* screwed thereon. The roller or wheel *a* is supported by hanging bearings *h* attached to the under 85 surface of the table *b*. From an inspection of the Figure 1 it will be seen that the discs constituting the grooving or scoring means are so arranged as to produce at the edge of the leather under treatment a bevel some- 90

what corresponding to that of the roller or wheel *a* but in a reverse direction, and at a less inclination in order that the space between the roller or wheel *a* and the grooving or scoring means is greater at that part where the roller or wheel *a* is of smaller diameter than the part of larger diameter. In thus forming the said space it approximately corresponds with the shape in cross section of the bevelled or chamfered margins of the pieces of leather or soles. The discs *c* are provided with suitable forms of projections such as shown in Figure 2, wherein the projections are formed with outer cutting edges *c'* of the same radius or as shewn in Figure 3 in which the projections *c²* on the disc *c⁴* are formed with outer cutting edges the radius of which decreases from one side edge of the tooth to the other side edge thereof. The discs are provided with apertures *c³* for facilitating their attachment to the shaft *d* which may be suitably supported in a bearing *j* carried on the upper part of the table.

The arrangement of the supporting means is such that the bevelled margin of the leather or sole can be evenly grooved or scored to meet varying requirements, the discs constituting the grooving or scoring means being capable of variation to meet the same.

30. What I claim and desire to secure by Letters Patent of the United States is:—

31. A machine for grooving and scoring leather, comprising a bevelled rotatable roller with one end of larger periphery than the other end, a table with an aperture therein, supports securing the roller to the table with a part of the larger periphery of the roller protruding through the aperture from the top of the table, and a grooving and scoring member disposed above the roller and rotatable in the same plane as that of the roller.

32. A machine for grooving and scoring leather, comprising a bevelled rotatable roller with one end of larger periphery than the other end, a table with an aperture therein, supports securing the roller to the under side of the table with the upper part of the larger periphery of the roller projecting through the aperture above the top of the table and the top part of the smaller periphery of the roller being in line with the said top of the table, and a grooving and scoring member disposed above the roller and rotatable in the same plane as that of the roller.

33. A machine for grooving and scoring leather, comprising an inclined table with an aperture therein, a bevelled rotatable roller with one end of larger periphery than the other end, the bevel of the roller being greater than the inclination of the table, supports securing the roller to the table with the upper part of the larger periphery of the roller protruding through the aperture from the top of the table, and a grooving and scoring member

disposed above the roller and rotatable in the same plane as that of the roller.

4. A machine for grooving and scoring leather comprising an inclined table with an aperture therein, a bevelled rotatable roller with one end of larger periphery than the other end, the bevel of the roller being greater than the inclination of the table, supports securing the roller to the under side of the table with the upper part of the larger periphery of the roller projecting through the aperture from the top side of the table and the top part of the smaller periphery of the roller being in line with the top of the table, and a grooving and scoring member disposed above the roller and rotatable in the same plane as that of the roller.

5. A machine for grooving and scoring leather comprising an inclined table with an aperture therein, a bevelled rotatable roller with one end of larger periphery than the other end, the bevel of the roller being greater than the inclination of the table, supports securing the roller to the table with the upper part of the larger periphery of the roller protruding through the aperture from the top of the table, and a grooving and scoring member disposed above the roller and rotatable in the same plane as that of the roller and composed of a series of toothed discs and a circular cutter.

6. A machine for grooving and scoring leather comprising an inclined table with an aperture therein, a bevelled rotatable roller with one end of larger periphery than the other end, the bevel of the roller being greater than the inclination of the table, supports securing the roller to the under side of the table with the upper part of the larger periphery of the roller projecting through the aperture from the top side of the table and the top part of the smaller periphery of the roller being in line with the top of the table, and a grooving and scoring member disposed above the roller and rotatable in the same plane as that of the roller and composed of a series of toothed discs arranged with the teeth of the several discs staggered and including a disc with a peripheral cutting edge.
